UNITED STATES PATENT OFFICE.

EDWIN D. HILTON, OF PATERSON, NEW JERSEY, ASSIGNOR OF ONE-HALF
TO WALTER BAMFORD, OF SAME PLACE.

LOOM.

SPECIFICATION forming part of Letters Patent No. 425,379, dated April 8, 1890.

Application filed January 31, 1889. Serial No. 298,240. (No model.)

To all whom it may concern:

Be it known that I, EDWIN D. HILTON, of Paterson, in the county of Passaic and State of New Jersey, have invented a new and useful Improvement in Looms, of which the following is a specification, reference being had to the accompanying drawings.

I will first describe the improvement fully in detail, and afterward point out its novelty in claims.

Figure 1 is a front view of all the parts of a loom necessary to illustrate the invention, the breast-beam and the front part of the framing being taken away to expose the parts behind them to view, and all the moving parts not involved in the improvement being omitted. Fig. 2 is a right-hand end view corresponding with Fig. 1. Fig. 3 is a back view of the same. Fig. 4 represents a vertical section parallel with the side of the loom in the line xx of Figs. 1 and 3, viewed from the right of Fig. 1 and from the left of Fig. 3. Fig. 5 is a sectional view taken nearly on the line yy of Figs. 1 and 3. Fig. 6 is a front view of the swivel-rack on a larger scale than the preceding figures. Fig. 7 represents a transverse section taken on the line zz of Fig. 6. Fig. 8 is a front view of the gearing, by which what is called the "skip" or "mock" movement of the swivel-shuttles and their operating mechanism is produced. Fig. 9 is a front view of the devices for shifting parts of the shuttle-operating mechanism from each to the other of the positions for plain weaving and swivel weaving. Figs. 10 and 11 are views of the outer sides of the two cams for operating the swivel-shuttles, and Fig. 12 is a side view of one of the cams for depressing the swivel-shuttle rack.

Similar letters of reference designate corresponding parts in the several figures.

A designates the framing of the loom; B, the main shaft; C, the lay; D, the reed; E E', the picker-sticks for the fly-shuttles, all of which parts may be the same as in ordinary looms for plain weaving.

F designates a cam-shaft, which is represented as occupying the same position as the cam-shaft of an ordinary loom for plain weaving and driven by gearing from the main shaft, B, as will be hereinafter described.

This shaft carries cams $i i'$ and $k k'$ for operating the swivel-shuttles, as will be herein-after described; and its gears $F' F^2$, through which it derives motion from the main shaft, 55 carry the cam-rollers $f f'$ for operating the body or fly-shuttle treadles $S S'$. These treadles may be connected with the picker-sticks in any well-known or suitable manner. They are represented as connected by straps 60 $b b'$, and the picker-sticks are represented as connected with the rock-shaft C' of the lay by springs $d d$, as is common in fly-shuttle looms.

G designates a horizontal bar or plate which 65 forms the main support for the swivel-shuttles and parts of their operating mechanism, the said bar and its appurtenances being commonly termed the "swivel-rack." The said bar is firmly secured to two rods G' , which 70 are fitted to slide up and down in guides c , fixed upon the back of the lay. The upper part of these rods are curved in goose-neck form to pass over the reed and the lay cap, as shown in Figs. 2 and 4. To the back of 75 this bar G is secured a slide G^2 , and to the bottom of this slide are secured a series of plates g , which constitute the raceways for the swivel-shuttles H. Pivoted to the said slide G^2 are toothed pinions g' , which engage 80 with toothed racks on the swivel-shuttles and also with a sliding toothed rack g^2 , by the reciprocating movement of which the said shuttles are driven through the pinions g' . This toothed rack g^2 is confined in proper relation 85 to the rack-bar G and slide G^2 by a covering-plate g^3 , in which there is a slot g^4 through which protrudes an eye g^5 , with which is connected cords g^6 for driving the toothed rack g^2 , which cords pass over a series of guide-pulleys $g^7 g^8 g^9$ and connect with the swivel-operating treadles I I'. The guide-pulleys g^7 are attached to the slide g^2 , as will be herein-after described. The guide-pulleys $g^8 g^9$ are attached to the lay. The treadles I I', being 95 alternately depressed by their respective cams $i i'$, pull the cords g^6 in one direction and in the other alternately, and so produce a reciprocating longitudinal movement of the rack g^2 , which, through the pinions, operate the swivel-shuttles in the usual manner. 100

The swivel-operating treadles I I' are each

furnished with a roller i^2 , upon which its respective cam i or i' operates. These cams are both of the same form, as shown in Figs. 10 and 11, and each has a circular hub upon which its respective roller may bear when the cam is not intended to operate, and the treadles I I' are moved out of operative position. The hub i^2 of the cam i is of a circumference corresponding with the shortest radius of the cam; but the hub i^3 of the cam i' is extended in the form of a disk of a circumference corresponding with its longest radius, as shown in Figs. 10 and 11, so that when the treadles are intended to be at rest, one elevated and the other depressed, as shown in Fig. 4, the roller of each rests on the circular hub of its respective cam.

- K K' designate the treadles upon which the cams k k' hereinbefore mentioned act to bring down the swivel-rack G, and the swivel-shuttles and their operating mechanism to their operative level in front of the reed. The rods G' G' are connected with these treadles by rods g^{10} . When not depressed by these treadles, the rack and the swivel-shuttles and their immediate appurtenances are raised to the position shown in Figs. 1, 2, 3, and 4 by means of spiral springs c' , which are coiled around the rods G', between their lower guides c^2 and the collars c^2 upon the said rods. The two cams k k' are alike, and as both operate together they are practically a single cam, and therefore it is obvious that a single cam of the same form and a single treadle might be substituted for the two cams k k' and two treadles K K', the two rods G' G' being in such case connected by a yoke cross-bar and the latter being connected with the single treadle.
- 40 The fly-shuttle treadles S S' and the treadles I I' and K K', for operating the swivel-shuttles, are all pivoted upon a horizontal shaft J, which is supported in fixed bearings a on the back part of the loom-framing, and they are confined to the said shaft in a direction lengthwise thereof between collars j j thereon, so that they may all move together with the said shaft when it is moved lengthwise, as herein-after described, for the purpose of changing 45 the relation between the said treadles and their respective cams for changing the operation from plain weaving to swivel-weaving without moving the cam-shaft lengthwise. The treadle-shaft J has a constant rotary motion, which is entirely independent of the treadles, at a speed corresponding with that of the cam-shaft F, the said rotary motion being derived from the cam-shaft through gears F* and J*, one fast on each shaft. One of the gears F* J* (the gear F* on the cam-shaft in the example represented) is made wide enough to allow the two to remain always in gear notwithstanding the lengthwise movement of the shaft J*.
- 55 The cam-shaft F has fast upon it at one end a gear F' and at the other end a larger gear F², and each of these gears with one of the

two gears B' B², which are so arranged upon the main shaft B that either may be made fast to the said shaft and the other left loose thereon. In the example represented each is furnished with a set-screw e , which may be screwed up to make it fast when it is required to drive or unscrewed to leave it loose when the other is required to drive. The gears B' and F' are so proportioned as to give the cam-shaft one revolution for every two revolutions of the main shaft, and the gears B² and F² are proportioned to give the cam-shaft one revolution for every four revolutions of the main shaft. The faster motion is to be given to the cam-shaft when plain weaving only is performed, and the slower motion when swivel weaving also is to be performed. In this way the same loom may be used to 85 perform plain weaving as fast as an ordinary loom for that purpose, or may be used for swivel-weaving with the desirably slower motion of its other parts, relatively to that of the main shaft and lay for that kind of 90 weaving.

The lengthwise movement of the treadle-shaft J, hereinbefore described, for the purpose of effecting the changes of relation of the treadles to the cams for plain weaving and swivel-weaving is effected by means of a double cam L (see Figs. 3 and 5) on the said shaft J and a reversible engaging device for engaging with the said cam. The said reversible engaging device is represented as 100 consisting of an inverted-T-shaped tumbler M, (see Figs. 3, 4, and 9,) which is pivoted by a pivot l' to a stationary bracket l , secured to the loom-framing, and from which are suspended two fingers m m' , which are guided 105 in guides in the bracket l , and either of which is capable of being engaged with the said cam while the other is disengaged therefrom. This double cam has two sets of similar, but reversely-arranged grooves n o p and n' o' p' , 110 each set consisting of a groove n or n' , which runs uninterruptedly directly around the cylinder in a plane perpendicular to the axis thereof, a groove o or o' parallel with its respective groove n or n' , and an oblique groove p or p' , forming a cross-over communication 115 between the grooves n o or n' o' .

The tumbler is to be operated by suitable connections, as wires q q' , (see Fig. 3,) with a pattern-producing mechanism—such as a Jacquard machine—so as to bring either the finger m or that m' into engagement with its respective set of grooves n o p or n' o' p' in the cam, the other finger being at the same time disengaged from the cam. When the shaft 125 J is in position for the treadles I I' and K K', to be in range with their respective cams i i' and k k' , as shown in Figs. 3 and 5, the finger m' is in the uninterrupted groove n' and the finger m entirely out of range of the cam, as 130 shown in Fig. 3, and no longitudinal movement of the treadle-shaft J takes place; but when it is desired to throw the swivel-shuttles out of operation the wire q' is pulled up, and

the tumbler M is thrown over to the left to take the finger m' out of the groove n' and bring the finger m into the groove o . The continued rotation of the treadle-shaft J then 5 brings the oblique cross-over groove p to the finger m and causes the cam to move laterally on the said finger, and so to move the treadle-shaft J lengthwise to the left of the position shown in Figs. 3 and 5, and thus take the 10 treadles I I' and K K' out of range of their respective cams. The finger m having arrived in the groove n the rotation of the treadle-shaft J continues without any operation of the treadles I I' and K K' until the 15 swivel-shuttles are required to operate again, when the wire q is pulled up and the tumbler M again thrown over to the right, and the finger m is disengaged from the cam and the finger m' caused to enter the groove o , when 20 the continued revolution of the treadle-shaft produces its movement to the right by an operation precisely the reverse of that just described with reference to its movement to the left, and the treadles I I' and K K' are again 25 brought within range of their cams $i i'$ and $k k'$. A spring s connects the tumbler M above its pivot l' with the bracket l in such manner as to hold it in either of the two positions by which it may be thrown over by the 30 wires $q q'$.

The longitudinal movement of the treadle-shaft J, besides taking the swivel-treadles I I' and K K' into and out of range with their respective cams, also takes the fly-shuttle treadles S S' into and out of range with two sets of cam-rollers f and f' carried by the gears F' and F^2 , the one set for operating the said treadles while plain weaving only is being performed, during which operation the 35 fly-shuttles require to make four picks for every revolution of the cam-shaft, and the other set for operating the said treadles when the operations of plain and swivel weaving are being performed, during which operations 40 the fly-shuttles require to make but two picks for every revolution of the cam-shaft, the operations of the fly-shuttles and the swivel-shuttles in the latter case alternating with each other. The arrangement of the cam-rollers $f f'$ for this purpose may be understood 45 by reference to Figs. 2, 3, and 5. On one side of the loom there are two cam-rollers $f f'$, arranged diametrically opposite each other, as shown in Fig. 2. The roller f on the right 50 side of the loom (see Fig. 1) is set out so far from the gear F^2 , which carries it, that when the treadles are in position for swivel-weaving, as shown in Fig. 1, the said roller will in its revolution pass outside of the treadle S on 55 that side of the loom without operating the said treadle, yet the said roller will operate on the said treadle when the treadle is moved outward by the longitudinal movement of the shaft J to the position for plain weaving. 60 The roller f' on the same side of the loom is long enough in the direction of its axis to operate on the treadle S in either of the posi-

tions of the latter, and hence it always operates. On the other side of the loom there are three rollers $f f' f'$. This roller f stands out 70 so far from the gear F' , which carries it, that it will only operate on the treadle S' when the treadle-shaft J and all its treadles are in position for swivel-weaving, as shown in Figs. 1, 3, and 5. These two rollers $f f'$, which are 75 diametrically opposite each other, one before and the one behind the roller f , on the same side, are so close to the gear F' that they will both operate on the treadle S only when the shaft J and all its treadles are in operation 80 for plain weaving.

In order to provide for what is known as the "skip" or "mock" motion of the swivel-shuttles, which is necessary to change the position widthwise of the warp of the figures 85 to be produced by the said shuttles, the slide G^2 is so secured, as shown in Figs. 6 and 7, to the rack-bar G by bolts t , passing through slots t' in the said bar G, but secured firmly by nuts t^2 to the slide G^2 , that the said slide 90 and all its attached parts, including the raceways, the shuttles, the toothed rack g^2 , pinions g' , and pulleys g^3 , may move a certain distance crosswise of the loom. In order to provide for effecting this movement, there is 95 secured to the back of the slide a short horizontal toothed rack u , (see Fig. 7,) which gears with a pinion u' , which turns freely on an upright stud u^2 , secured fixedly in or on the lay-cap D', and which gears with a face-toothed wheel u^3 , which is capable of turning 100 freely on a stud u^4 , secured in a standard u^5 , which is erected firmly on the lay-cap D'. This standard carries also another stud u^6 , on which turns a toothed sector u^7 , which gears 105 with a toothed sector u^8 , which is secured to or integral with the toothed wheel u^3 . By turning this sector u^7 in one direction or the other on its pivotal stud u^6 it will be made to turn the sector u^8 and the wheel u^3 , and 110 through the latter to turn the pinion u' , and so, by the action of the latter on the rack u , to produce the movement of the slide G^2 , and the swivel-shuttles, their raceways, and pinions g' in one direction or the other. 115

The movement of the sector u^7 for effecting the skip or mock movement above described is to be produced by suitable connections—as rods, wires, or cords $v v'$ —with any suitable pattern mechanism—as, for instance, a 120 Jacquard machine. The said sector is held in either of the positions to which it may be moved by the connections $v v'$ by means of a spiral spring u^9 , which is connected with it above its pivotal stud u^6 , and also connected 125 with the pivotal stud u^4 of the wheel u^3 and sector u^8 .

In order that the pinion u' may always remain in gear with the toothed rack u ; notwithstanding the rising and falling movement of swivel-shuttles and their supporting and operating mechanism, the said rack is made of a width equal to the said rising and falling movement added to the width of the 130

pinion, as may be understood by reference to Fig. 7.

In order to take up the slack of the cord g^6 , or rather to avoid the slackness which would occur in the said cord owing to the mock motion unless some means of preventing it were provided, the guide-pulleys g^7 for the said cord are pivoted to arms t^8 , which are pivoted to the sliding plate or bar G^2 . The bolts t , hereinbefore described, are represented made to serve as the pivots for the said arms. The said arms are drawn by the said cords against fixed stops t^4 , provided on the bar or plate G on the outer sides of said arms, and as the slide G^2 moves in one direction or the other the arm t^8 , which is in advance in the direction in which the bar moves, is pressed against its stop t^4 and so caused to be moved toward a vertical position and so take up its cord, while the other arm is allowed to fall away from the vertical position, and thereby let out its cord. This action may be better understood by reference to Fig. 6, in which the slide G and its attached parts are supposed to be in their extreme left-hand positions when the left-hand cord g^6 is taken up and the right-hand one let out.

What I claim as my invention, and desire to secure by Letters Patent, is—

1. The combination, with the swivel-rack and the swivel-shuttles, of a cam-shaft and two sets of cams thereon, one set for producing the movements of the swivel-shuttles and the other for producing the downward movement of the swivel-rack, two sets of treadles to be operated upon by said cams, and mechanism, substantially as described, actuated by said treadles for producing said movements, a treadle-shaft upon which all of said treadles are pivoted, but are confined in the direction of its length, and which is capable of a rotary and longitudinal motion, gearing for producing the constant rotation of the treadle-shaft, a double cam on the treadle-shaft, and a reversible engaging device, substantially as herein described, engaging with said double cam for the purpose of moving the treadle-shaft lengthwise, as herein described, to place the treadles in operative and inoperative relation to said cams on the cam-shaft, substantially as herein set forth.

2. The combination, with the swivel-rack, the swivel-shuttles, and the body-shuttles, of a cam-shaft and three sets of cams thereon, one set for driving the swivel-shuttles, a second set for depressing the swivel-rack, and a third for driving the body-shuttles, three sets of treadles upon which the said cams respectively operate, and mechanism, substantially as herein described, for the actuation of the swivel-shuttles, swivel-rack, and body-shuttles from the said treadles, a treadle-shaft to which all of said treadles are pivoted, but are confined in the direction of its length, gearing for producing a constant rotary motion of

the treadle-shaft, a double cam on the treadle-shaft, and a reversible engaging device, substantially as herein described, engaging with said double cam for the purpose of moving the treadle-shaft lengthwise, as herein described, to place the first and second sets of treadles in operative and inoperative relation to their respective cams, and to place the third set of treadles in proper relation to their respective cams for plain and swivel weaving, as herein set forth. 70

3. The combination of the lay, the swivel-shuttle rack, the swivel-shuttles, the pinions g' , toothed rack g^2 , two treadles II' , and cords g^6 , of the rotary cam-shaft F , and the cams i i' thereon for operating the said treadles, the treadle-shaft J upon which the said treadles are pivoted, but confined lengthwise thereof, the gearing $F^* J^*$ between the cam-shaft and treadle-shaft for producing the rotary motion 80 of the treadle-shaft, the double cam L on the treadle-shaft, and the reversible engaging device $M m m'$, attached to the loom-framing, engaging with said cam to produce a longitudinal movement of the treadle-shaft for 85 placing the treadles in operative or inoperative relation to the cams i i' , substantially as herein specified.

4. The combination of the picker-treadles $S S'$, the cam-shaft F , and rollers $f f'$, carried by said shaft for operating said treadles, the main shaft B , and the two sets of gears $B' F'$ and $B^2 F^2$ between said main shaft and cam-shaft, and means, substantially as described, for engaging either set of gears with the main shaft, and disengaging the other to provide for the driving of the cam-shaft at different velocities for plain weaving or swivel-weaving, all substantially as herein described. 95

5. The combination, with the swivel-rack, its slide G^2 , and the lay, of the toothed rack u on the back of the said slide, the pinion u' , pivoted to the lay and gearing with said rack, the toothed wheel u^3 , pivoted to the lay and gearing with said pinion, the toothed sector u^8 , attached to said wheel u^3 , and the toothed sector u^7 , pivoted to the lay, gearing with said sector u^8 , and adapted to be operated by pattern mechanism for producing the skip or mock movement, all substantially as herein described. 100

6. The combination, with the swivel rack-bar G , the slide G^2 , and the toothed rack g^2 , cords g^6 , treadles II' , rotary cam-shaft F , and cams i i' for driving the swivel-shuttles, of the guide-pulleys g^7 , the arms t^8 , pivoted to the said slide G^2 and carrying said guide-pulleys, and the stops t^4 on the rack-bar, substantially as and for the purpose herein set forth. 110
